UNITED STATES PATENT OFFICE

EMIL R. KLEMM, JR., AND FREDERICK O. SINGER, OF CHICAGO, ILLINOIS, ASSIGNORS, BY
MESNE ASSIGNMENTS, TO KLEMM AUTOMOTIVE PRODUCTS COMPANY, OF CHICAGO,
ILLINOIS, A CORPORATION OF ILLINOIS

GOVERNOR

Application filed November 4, 1929. Serial No. 404,825.

The invention relates to governors and more particularly it relates to governors for hydro-carbon motors of the type actuated by the flow of fluid in the intake of a motor or 5 the like.

Still more particularly the invention relates to mechanism adapted to provide resistance for an unbalanced butterfly valve positioned in the intake of the motor in the path of the 10 inflowing fluid.

It includes among its objects and advantages the provision of a vacuum release opening when the valve is closed, and a convenient mounting for the valve member proper, all in a single unitary structure; also a configuration of the surface of the valve facing the incoming stream, of particular advantage in securing effective operation.

In the drawing, wherein like reference 20 characters indicate like or corresponding parts:

Fig. 1 is a plan and partial sectional view of the device;

Fig. 2 is a section taken along the line 2—2 25 of Fig. 1;

Fig. 3 is a section taken along the line 3—3 of Fig. 1;

Fig. 4 is a section taken along the line 4—4 of Fig. 1; and

Fig. 5 is a sectional view illustrating another form of butterfly valve.

Referring now to the drawing, the governor includes a casing 11 normally interposed between a tubular member 12 leading to 35 the engine and a tubular member 13 leading from the carburetor. Any suitable means may be employed for attaching the tubular members 12 and 13 to the casing 11, flanges 14 and 15 being shown as secured to the casing 40 by means of bolts 16.

A spindle or shaft 19 extends across a rectangular passage 17 in the casing 11 to provide a mounting for a plate 18, which is fastened to the shaft by means of screws 26 or the like. The fastening of the plate 18 to the spindle 19 creates an unbalanced valve so that the pressure of gas flowing upwardly through the passage 17 tends to move the plate to its closed position. The spindle 19 is substantially circular in cross section and

is mounted in close proximity to the side wall of the casing 11. The portion of the spindle within the passage 17 has two segments cut away, a large segment on the left as seen in Figure 4 to form a support for the valve 18, 55 and a smaller segment on the right leaving the flat face 35. When the plate 18 is moved to its uppermost position, the face 35 is parallel to and spaced away from the adjacent wall of the casing 11 and provides an opening 36 acting as a vacuum release. When the plate 18 is in its downward position the convex portion of the shaft is in sufficiently close proximity to the side wall of the casing 11 to substantially close the opening 36 and 60 prevent gas from passing the valve.

The initial flow of the fluid upwardly through the aperture 17 creates an unbalanced pressure upon the plate 18, tending to move the plate towards its closed position. 70

The plate 18 is shown with an integral lateral flange or baffle extending transversely across substantially its entire width in general parallelism with the pivot. The baffle 30 is on the side facing the incoming stream, and is slightly spaced from the outer edge of the valve plate 18. It thus defines a relatively small rectangular pocket opening downward and away from the pivot, and another larger pocket opening toward the 80 pivot.

We have found that in the absence of the baffle 30, the plate 18 tends to be somewhat unstable in certain intermediate positions, and that the presence of the baffle eliminates this instability. We believe the reason for this to be that the baffle shields the gas in the space defined by the larger pocket, in which gas the impact of the rising stream would otherwise set up a large and violent eddy current or vortex.

One end of the spindle 19 projects through a wall of the casing 11 into a housing 20. The housing 20 is fastened to the casing by 95 means of a plurality of bolts or screws 28. A wall 27 of the housing 20 is removable to provide access to the interior of the housing. A lever 21 is fixedly mounted on the projecting end of the spindle 19 and is rotatable 100 within the housing. A pin 22 provides a

stop limiting the downward movement of the free end of the lever 21 and thereby also limits the downward movement of the butterfly plate 18.

- 5 A spiral spring 25 is fastened to the lever 21 near its point of connection with the spindle 19 by means of a pin 29. The other end of the spring 25 is fastened to the lower end of a threaded screw or bolt member 23.
- 10 The member 23 is mounted on an interiorly threaded member 24. The upper end of the member 23 projects through the upper wall of the housing 20. A slot 33 in the upper end of the member 23 enables the member 15 to be turned by means of a screw-driver or the like for adjustment. In Fig. 2 the member 21 is shown in full lines in its lowermost position and in dotted lines in substantially its uppermost position. For this position of 20 the member 23 there is relatively slight or no tension in the spring 25, the spring being maintained in a substantially straight line by the weight of the unbalanced butterfly 25 valve and extending downwardly in a direction tangential to the upper curved surface of the lever 23 at its point of connection with arm 21.

The flow of fluid through the passage 17 30 rotates the plate 18 towards its closed position, such rotation being resisted by the spring 25. As the plate 18 rotates towards its closed position it presents a constantly increasing pressure area to retard the flow 35 of fluid and a correspondingly greater force is thereby exerted upon the spring 25. As the plate 18 rotates upwardly the corresponding rotation of the lever 21 will cause the adjacent portion of the spring 25 to wrap 40 about the upper curved surface of the lever. This wrapping of the spring 25 about the upper surface of the lever 21 increases the effective length of the lever, such effective length at any instant being the distance from 45 the center of the spindle 19 to the middle of that portion of the spring then in bearing contact with the lever 21. As a result, the higher the plate 18 is moved, the greater the resistance offered by the spring 25 and the 50 lever 21 to any further rotation of the plate 18. The spring 25 and the arm 21 are so constructed as to counterbalance the pressure on the plate 18 in some predetermined position, leaving a correspondingly predetermined portion of the passage 17 free for the 55 flow of fluid.

If it is desired to increase the maximum effective speed of the engine, the upward movement of the plate 18 is limited so that 60 a greater portion of the aperture 17 will be open to the passage of fluid. This result is accomplished by threading the bolt member 33 downwardly through its mounting 24 and thereby increasing the initial tension of 65 the spring 25 as well as increasing the effec-

tive length of the arm 21 for the initial movement of the plate 18. The further down the bolt 23 is threaded the greater is the initial resistance offered by the spring 25 to the turning of the plate 18, and the amount of rotation of the plate 18 will be correspondingly limited so as to leave a larger open passage 17 for the counterbalanced position of the plate 18.

In Fig. 5 is shown a modified form of the 75 invention wherein the butterfly plate 31 is provided with a plurality of serrations 32 arranged to function as baffles. The serrations 32 retard the movement of air through the wedge shaped space between the plate 31 80 and the adjacent wall of the passage 17. As a result, the plate 31 responds more quickly to the pressure created by the upward flow of gas striking the under surface of the plate 85 and adds to the responsiveness of the device to slight changes in the flow of gas.

Having thus described my invention, it is obvious that various immaterial modifications may be made in the same without departing from the spirit of my invention; 90 hence, I do not wish to be understood as limiting myself to the exact form, construction, arrangement, and combination of parts herein described or uses mentioned.

What I claim as new and desire to secure 95 by Letters Patent is:

1. In a governing device of the kind described, a casing providing an intake conduit leading to a motor, a butterfly valve mounted within the conduit and having a shaft projecting through the casing, said shaft having an eccentric mounting, whereby said shaft is spaced away from the adjacent wall of the casing when the valve is in closed position and in substantial contact with said wall when the valve moves to open position.

2. In an automatic governor for internal combustion engines, a square passageway for delivering combustible mixture to an engine, a pivot flap valve in said passageway, having a straight edge remote from the pivot positioned to move against a wall of the passageway remote from the pivot, the face of said valve opposing the incoming gases having a straight shoulder parallel to said edge and offset therefrom a minor fraction of the distance from said edge to said pivot, said shoulder being defined by a transverse ridge generally parallel to the pivot defining a 115 pocket opening away from said pivot and another pocket opening toward said pivot.

3. In an automatic governor for internal combustion engines, a passageway for delivering combustible mixture to an engine, a 125 pivotal flap valve in said passageway, having an edge remote from the pivot positioned to move against a wall of the passageway remote from the pivot, the face of said valve opposing the incoming gases having a shoul-

der, said shoulder being defined by a transverse ridge extending generally parallel to the pivot and substantially across the entire width of the valve defining a pocket opening 5 away from said pivot and another pocket opening toward said pivot.

4. In an automatic suction-operated speed control for internal combustion engines, a 10 passageway for conveying explosive mixture to an engine, a pivot in said passageway near one side thereof, and a butterfly valve on said pivot, the portion of the valve adjacent the pivot, and the adjacent wall of the passage being shaped so that rotation of the valve to 15 closed position opens a relatively small passageway between the pivot and the adjacent wall of the passageway.

5. In a suction-actuated automatic speed governor for internal combustion engines, a 20 casing having an intake conduit with at least one flat side, a shaft journaled in said casing and extending transversely across said conduit in close proximity to said flat side, the portion of said shaft extending across said 25 conduit having a segment cut away on one side to open and close a passage between said shaft and casing as the shaft is rotated.

6. In a suction-actuated automatic speed governor for internal combustion engines, a 30 casing having an intake conduit with at least one flat side, a shaft journaled in said casing and extending transversely across said conduit in close proximity to said flat side, the portion of said shaft extending across said 35 conduit having a segment cut away on one side to open and close a passage between said shaft and casing as the shaft is rotated, and another segment cut away on the other side of said shaft to form a seat for an unbalanced 40 flap valve.

7. In a suction-actuated automatic speed governor for internal combustion engines, a 45 casing having an intake conduit, an unbalanced valve in said conduit, a rotary shaft for said valve extending through said casing and having one projecting end only, walls defining a compartment housing the projecting end, one of said walls lying in a plane parallel to but remote from the axis of said 50 shaft, screw threaded adjustment means adjacent to and operating parallel to said last mentioned wall, and externally accessible for adjustment at one corner of said compartment, and a resilient control connection between said adjustment means and the said shaft, arranged to have its effective resistance to shaft movement increased by movement of said screw adjustment means away from the point of adjustment, and decreased by 55 movement in the opposite direction; said connection including a resilient element, a rigid arm on said shaft, and a connection between said element and said arm arranged to vary the direction of force of the spring element, and the portion of the 60

spring element bearing against the arm, as the arm rotates about the axis of the shaft.

8. In a suction-actuated automatic speed governor for internal combustion engines, a 70 casing having an intake conduit, an unbalanced valve in said conduit, a rotary shaft for said valve extending through said casing and having a projecting end, walls defining a compartment housing the projecting end, one of said walls lying in a plane parallel to but remote from the axis of said shaft, screw threaded adjustment means adjacent to and operating parallel to said last mentioned wall, and externally accessible for adjustment at one corner of said compartment, and a 75 resilient control connection between said adjustment means and the said shaft, arranged to have its effective resistance to shaft movement increased by movement of said screw adjustment means away from the point of adjustment, and decreased by movement in the opposite direction.

9. In a suction-actuated automatic speed governor for internal combustion engines, a 80 casing having an intake conduit, an unbalanced valve in said conduit, a rotary shaft for said valve extending through said casing and having a projecting end, walls defining a compartment housing the projecting end, one of said walls lying in a plane parallel to but remote from the axis of said shaft, screw threaded adjustment means adjacent to and operating parallel to said last mentioned wall, and externally accessible for adjustment at one corner of said compartment, and a resilient control connection between said adjustment means and the said shaft, arranged to have its effective resistance to shaft movement increased by movement of said screw adjustment means away from the point of adjustment, and decreased by movement in the opposite direction.

10. In a suction-actuated automatic speed governor for internal combustion engines, a 90 casing having an intake conduit, an unbalanced valve in said conduit, a rotary shaft for said valve extending through said casing and having a projecting end, walls defining a compartment housing the projecting end, one of said walls lying in a plane parallel to but remote from the axis of said shaft, screw threaded adjustment means adjacent to and operating parallel to said last mentioned wall, and a resilient control connection between said adjustment means and the said shaft; said control connection including a resilient element, a rigid arm on said shaft, and a connection between said element and said arm arranged to vary the direction of force of the spring element as the arm rotates about the axis of the shaft.

11. In a suction-actuated automatic speed governor for internal combustion engines, a 110 casing having an intake conduit, an unbalanced valve in said conduit, a rotary shaft 115

for said valve extending through said casing and having a projecting end, walls defining a compartment housing the projecting end, one of said walls lying in a plane parallel to but remote from the axis of said shaft, screw threaded adjustment means adjacent to and operating parallel to said last mentioned wall, a resilient control connection between said adjustment means and the said shaft; said control connection including a resilient element, a rigid arm on said shaft, and a connection between said element and said arm arranged to vary the spring tension and the direction of force of the spring element as the arm rotates about the axis of the shaft; and a cover closing said compartment, said screw adjustment means extending to one corner of the compartment and at that corner being accessible for manual adjustment without removing said cover.

12. In a suction-actuated automatic speed governor for internal combustion engines, a casing having an intake conduit with at least one substantially flat side, a shaft journaled in said casing and extending transversely across said conduit in proximity to said flat side, an unbalanced valve on said shaft and in said conduit, said shaft having a projecting end, walls defining a compartment housing the projecting end, one of said walls lying in a plane parallel to but remote from the axis of said shaft, screw threaded adjustment means adjacent to and operating parallel to said last mentioned wall and including a male threaded member parallel to said wall, and a female threaded member receiving said male member and restrained against rotation and movable parallel to said last mentioned wall by rotation of said male member, and a resilient control connection between said female element and said shaft; said control connection including a resilient element, a rigid arm on said shaft, and a connection between said element and said arm arranged to vary the spring tension as the arm rotates about the axis of the shaft; and a cover closing said compartment, said male threaded member extending through one corner of said compartment and at that corner being externally accessible for rotary adjustment without removing said cover, said shaft, valve, and rigid arm being limited to a rotary movement less than ninety degrees.

In witness whereof, we hereunto subscribe our names this 31st day of October, A. D. 1929.

EMIL R. KLEMM, JR.
FREDERICK O. SINGER.

DISCLAIMER
